(57) **CLAIM**

We claim the ornamental design for a data card, as shown and described.

DESCRIPTION

FIG. 1 is a perspective view of a data card showing our new design.

FIG. 2 is a top plan view of the data card as shown in FIG. 1 showing our new design.

FIG. 3 is a front elevational view of the data card as shown in FIG. 1 showing our new design.

FIG. 4 is a left side view of the data card as shown in FIG. 1 showing our new design.

FIG. 5 is a right side view of the data card as shown in FIG. 1 showing our new design.

FIG. 6 is a rear elevational view of the data card as shown in FIG. 1 showing our new design.

FIG. 7 is a bottom plan view of the data card as shown in FIG. 1 showing our new design.

FIG. 8 is a perspective view of a second embodiment of a data card showing our new design.

FIG. 9 is a top plan view of the data card as shown in FIG. 8 showing our new design.

FIG. 10 is a front elevational view of the data card as shown in FIG. 8 showing our new design.

FIG. 11 is a left side view of the data card as shown in FIG. 8 showing our new design.

FIG. 12 is a right side view of the data card as shown in FIG. 8 showing our new design.

FIG. 13 is a rear elevational view of the data card as shown in FIG. 8 showing our new design; and,

FIG. 14 is a bottom plan view of the data card as shown in FIG. 8 showing our new design.
